UNITED STATES PATENT OFFICE.

JAMES EDGAR LEE, OF GRAND HAVEN, MICHIGAN, ASSIGNOR TO THE CHALLENGE MACHINERY COMPANY, OF GRAND HAVEN, MICHIGAN, A CORPORATION OF MICHIGAN.

GALLEY LOCK.

Application filed April 3, 1922. Serial No. 549,271.

To all whom it may concern:

Be it known that I, JAMES EDGAR LEE, a citizen of the United States of America, residing at Grand Haven, in the county of 5 Ottawa and State of Michigan, have invented certain new and useful Improvements in Galley Locks; and I do hereby declare the following to be a full, clear, and exact description of the invention, such 10 as will enable others skilled in the art to which it appertains to make and use the same.

This invention relates to galley locks and is particularly concerned with the provision 15 of a very simple, inexpensive and especially effective lock of this character, which is very effective in use and presents no parts liable to be accidentally caught by the clothing of the operator while making up 20 his form between the lock and the head of the galley, together with a capability for storage of printing paraphernalia used in making up the form outside of the lock, temporarily, and generally simplify and 25 make more practical locks of this character. Another object of this invention is to provide a lock of the general character shown in the Jones Patent No. 1,366,663, granted Jan. 25, 1921, wherein the lock is held in 30 place by frictional contact at its ends against the sides of the galley, this invention including several improvements, both in structure and function, for the betterment of the working of the lock and greater 35 economy in manufacture. Various other objects, purposes and advantages of the invention will be apparent as understanding thereof is had from the following description, taken in connection with the accompanying drawing, in which,

Fig. 1 is a perspective view of a galley with my galley lock in place, parts being broken away and shown in section for better disclosure.

Fig. 2 is a horizontal section enlarged through the galley lock and fragmentary portions of the sides of the galley.

Fig. 3 is a transverse section through the galley lock on a plane adjacent and parallel to that shown by line 3—3, of Fig. 2, and

Fig. 4 is an end elevation of the galley lock.

Like reference characters refer to like parts in the different figures of the drawing.

55 The galley is of conventional construc-

tion having a bottom 1 and vertical sides 2, one end 3 being closed to make a head for the galley, between which and the galley lock the form made, indicated at 4, is held.

The galley lock which I have devised, 60 includes a hollow sheet metal bar, substantially square in cross section and of a length slightly shorter than the distance between the sides 2 of the galley. Near one end of the bar, two of its sides are slotted at 6 65 for a purpose which will hereafter appear. A rod 7 is placed inside and lengthwise of the bar 5, being of substantially the same length therewith. The ends of the rod are oppositely threaded and a nut 8 is carried 70 on and at each end of the rod. These nuts at their outer ends are formed with short circular bosses 9 which are designed to bear against the sides 2 of the galley when the lock is in operative position.

A collar 10 is located on the rod 7 at the slotted part at 6 in the bar 5. A handle 11 is formed at one end with a reduced threaded extension 12 adapted to be received in an interiorly threaded opening 80 made through the collar and rod. By moving the handle back and forth within the limits prescribed by the slot at 6, the rod 7 is given a partial rotation. The nuts 8 are held from rotation by reason of fitting 85 within the ends of the bar 5, and rotation of the rod 7 in one direction serves to project both nuts outwardly simultaneously, and in the other direction withdraws the same simultaneously. Accordingly, when 90 properly adjusted on the rod 7, said nuts are pressed against the sides 2 of the galley to frictionally engage therewith on movement of the handle 11 to the position shown in Fig. 1, and are released therefrom on 95 movement of the handle in the opposite direction.

The handle 11 is readily removed from connection with the collar 10 and rod 7, whereupon the rod with attached nuts 8 100 can be taken from the bar 5 that houses the same, and the nuts adjusted to different positions, either by a quarter or half turn of the same or more, should it ever become necessary to do so if the nuts do not sufficiently engage the galley sides when moved outwardly, or if they are not sufficiently withdrawn when the lock is released. By virtue of this construction, the lock is very 105 easy of assembly, as is evident. In fact, 110

the lock is particularly simple and economical to build, assemble and keep in order.

The handle 11 is located adjacent one end of the lock preferably, so that it will be 5 out of the way while the operator is setting up his form, the handle being as far away from the operator as possible and not at all liable to interfere with him in any way. A considerable space is left at 10 the left of the galley lock and below the handle for temporary reception of or storing of type, lines of type, rules, leads, slugs and other paraphernalia used by him in 15 making up a form, the galley lock in no way interfering. Simplicity in structure and operation, no change necessitated in the galley construction, easy adjustment and durability of construction combine to make 20 the lock one of exceptional value. And it has so proved in practice.

I claim:

1. A galley lock comprising an elongated hollow body, a rod oppositely threaded at its ends located within and lengthwise of 25 the body, nuts on the ends of the rod located at the ends of the body, and means for manually turning the rod from outside of the body.

2. A galley lock comprising a bar adapted 30 to be placed between the sides of a galley, a rod having oppositely threaded ends located lengthwise of the body, nuts on the ends of the rods held from rotation 35 by engagement with the bar, and means for manually turning the rod in opposite directions.

3. A galley lock comprising a hollow bar substantially square in cross section, a rod located inside and lengthwise of the bar, 40 nuts on the ends of the rod located in the

ends of the bar, said bar being slotted 45 through sides thereof, and a handle passing through the slot and connected with the rod for manually turning the same.

4. A galley lock comprising a hollow bar substantially square in cross section, a rod located inside and lengthwise of the bar, 50 said rod being oppositely threaded at its ends, nuts on the ends of the rod located in the ends of the bar, said bar being partly slotted transversely therethrough adjacent one end, and a handle passing through the slot and detachably connected with the rod for manual turning of the same.

5. A galley lock comprising a bar, a rod carried lengthwise of the bar, means carried at each end of the rod and associated with the bar whereby on turning the rod about its longitudinal axis said means may be simultaneously projected outwardly or simultaneously withdrawn, and means for 60 manually turning the rod in opposite directions to effect such projection or retraction.

6. A galley lock comprising a hollow bar, a rod having oppositely threaded ends located lengthwise of the bar, nuts in the 70 ends of the bar threaded on to the ends of the rod, a collar on the rod between its ends, said collar and rod having threaded openings therethrough, and a handle having a 75 threaded end entered into the openings in the collar and rod and extending outwardly through the bar, said bar being slotted to pass the handle and to permit a limited movement thereof to turn the rod.

In testimony whereof I affix my signature.

JAMES EDGAR LEE.
